SELF-PROPELLED BOMB

Samuel L. Conrad, Columbus, Ohio

Application January 26, 1942, Serial No. 428,201

5 Claims. (Cl. 102—19)

The invention to be hereinafter described relates to self propelled bombs.

Several types of self propelled bombs are known both for land and water use. One well known variety is the widely used torpedo for submarine warfare. As heretofore constructed, self propelled bombs have been made to travel in a given direction or predetermined path toward a predetermined object or target and at an approximately uniform rate of speed. Such bombs have been mechanically complicated and correspondingly costly. And, of course, when they did not hit their mark, a preselected target, as was frequently the case, they were ineffective and a total loss.

The main purposes of the present invention are to overcome the above and other objections and provide a simple, efficient, compact, self propelled bomb which may be readily produced in great quantities at low cost and which, when released, will travel erratically and irregularly, as though entirely out of control, so that an enemy can not anticipate its direction of travel, its rate of travel or its intended or probable destination or target.

The single figure of the drawing is a diametrical cross section through the invention along the axis of mounting of the power or driving unit showing diagrammatically or schematically, the power unit and immediately cooperating parts.

In addition to the destructive effect of the bomb, an added object or purpose of the present invention is that of creating fear and consternation. In the present invention that purpose is accomplished by causing the bomb to travel erratically, changing direction without apparent reason or system, such changes being entirely automatic and unpredictable by the enemy. Such a bomb, charged with high explosive, gas, or other war agent, released among enemy troops and darting first in one direction and then in another, liable to explosion or discharge at any instant, would have great terrifying effect in addition to its highly destructive explosive effect.

One very simple form of the invention is shown schematically or in diagram in the drawing and it is believed that such showing will be ample for illustration and a clear understanding, a great many changes, variations and modifications of that showing being, clearly, possible though all embodying the same present invention. On the other hand, further illustration, probably, would decrease clearness of disclosure rather than increase it. Therefore, further illustra-

tion in the drawing is unnecessary to fully convey the invention to those skilled in the art to which it relates.

Referring to the drawing in detail, 1 indicates the body of the bomb. It is a hollow ball or sphere and, therefore, capable of rolling or travelling in any direction and of changing that direction erratically to any other direction instantly. It may be made in any number of sections or parts and by any known process or method. A simple construction is two equal parts or half-spheres electrically welded together along their edges. Any other manner or means of connecting the parts may be used, of course. Electric welding is simple, efficient and relatively cheap. Within each such half-sphere is disposed a heavy strong wall or partition 2, welded or otherwise suitably secured to the inner face of that section. These two partitions are so placed or positioned in their respective sections as to be parallel to each other when the sphere sections are assembled. Extending through each sphere section from its outer surface and through its respective partition, perpendicularly to that partition, is a tubular bearing 3, suitably secured in place as by welding or other acceptable method. In assembled relation, these tubular bearings establish communication between the inside and the outside of the sphere. It will be noticed that, in assembled relation, partitions 2 divide the ball or sphere into three parts or chambers or compartments, two arcuate segments 4 and 5 and an intermediate zone, compartment or chamber 6. Segments 4 and 5 are adapted to be suitably charged with, receive or contain the bomb charge or charges. The manner or method of loading the charges into their respective compartments or chambers forms no part of the present invention. Any acceptable way or method may be used. Openings with suitable closures may be provided at any point in the partitions for such charging if desired. It is not believed either necessary or desirable to illustrate any form or arrangement of such well known details. It will also be obvious that the charges may be of any desired character—i. e. high power explosive for demolition, incendiary, gas, etc., etc. Also it will be clear that the bombs may be designed as time bombs of various kinds, bombs exploded by detonation, etc., etc.

The propelling power or driving unit may be any type acceptable of internal combustion engine 7 desired. This engine is mounted in the bearings 3 by free swinging tubular arms 8 and 9 which also constitute, respectively, the inlet

and exhaust of the engine. They are, of course, made heavier and stronger than the regular or standard inlet and exhaust connections or conduits and their connections to the engine are, necessarily, much stronger to carry the load and take up the strains of supporting the engine in that manner. To the usual power shaft of the engine 10 is made fast a gear 11 in mesh with and driving gear 12 fixed to arm 9. For simplicity, a single set of gears has been shown for driving the ball or sphere at relatively high speed. Any other ratio of gears desired may be used, as will be well understood. Likewise, two sets of gears could be used, one for high speed and one for low, with an automatic clutch to shift from one to the other all as will be well understood and need not be illustrated in detail in the drawing.

The fuel supply of the engine will be carried in the tank 13 of any acceptable form and construction, secured to and carried by the engine, a carburetor or mixer 14 being interposed in usual and well known manner in the gas supply line. Thus, the fuel supply tank, engine and carburetor or mixer form a unit.

In assembled relation, but with the engine not running, the engine and tank are in the position shown in the drawing, placing the center of gravity of the invention considerably below the bearings 3. Now, with the parts in the positions shown, assume that the engine has been started. The intermeshed gears will tend to lift the engine and tank in an arcuate path or swing them upwardly about the axial mounting 3, 3, 3. This shifts the center of gravity of the sphere and the ball rolls, and, of course, as the engine continues to drive, the center of gravity continues to shift and the ball continues to roll or travel to reestablish the former center of gravity. This will continue as long as the engine operates and the engine will continue to operate as long as its supply of fuel lasts.

Being a sphere, no amount of tipping to one side or another by surface contour or obstacles can overturn it or upset it. It can and will be deflected readily and easily so that it will automatically dodge or avoid many obstacles resulting in a very erratic path wholly unpredictable and incapable of being anticipated by an enemy. Its direction of travel is dependent upon its center of gravity and that changes with obstructions and contours met.

Since it is at all times in gear, the engine may be started by simply turning or rotating the sphere or shell which, of course, has the same effect as cranking an engine. To do this simply catch one or another of the ground gripping spikes 15 and swing. This is possible because the bomb is supported, when ready for use, in racks or other suitable means by axles, rods, pins or the like extending into the outer ends of the bearings 3. Such supports being no part of this invention, are not illustrated here. The particular bomb is moved into position for release, its shell is spun to start the engine and its supports are then withdrawn, launching the bomb. As the shell starts rotating, spikes 15 engage the surface and it starts to travel.

Due to their erratic travel, such bombs would be particularly effective when released in troop concentrations. Carried by planes, they could be dropped by parachute, the engine being started before discharge from the plane, the connection between parachute and bomb being such that the bomb would be automatically released from its parachute as it contacted the ground. Such

parachute connection being no part of this invention, it is not illustrated or further disclosed in this application. Any one of several such supports and automatic releases might be used, as desired. Due to the fact that the engine is running at time of contact with the ground, the shell 1 will be spinning as the bomb lands and will immediately run out from beneath the parachute, as will be well understood.

10 More than two partitions 2 may be used. In fact, any number desired may be used and, likewise, the interior of the shell may be divided into any desired number of chambers or compartments similar to 4 and 5.

15 It hardly need be added that the material used will be such that it will give the desired strength and durability necessary to meet all contingencies of the intended use, including the desired degree of fragmentation for high explosive bombs, where the invention is to be so used.

20 It is thought that the construction, operation and use of the invention will be clear from the preceding detailed description.

25 Many changes may be made in the construction, arrangement and disposition of the various parts of the invention within the scope of the appended claims without departing from the field of the invention and it is meant to include all such within this application, wherein only one preferred construction has been illustrated, purely by way of illustration and with no intention to in any degree limit the claim thereby.

30 Having thus disclosed my invention, what I claim and desire to protect by Letters Patent is:

35 1. A bomb construction comprising a spherical shell, spaced parallel partitions within said shell dividing the same into chambers, tubular bearings extending diametrically through said shell and partitions, and in the space between said partitions an internal combustion engine revolvably mounted in said bearings and hanging therebelow in free swinging relation and driving connections between said engine and one of said bearings.

40 2. A bomb construction comprising a spherical shell, spaced parallel partitions within said shell dividing the same into chambers, tubular bearings extending diametrically through said shell and partitions, an internal combustion engine revolvably mounted in said shell, inlet and exhaust conduits fixed to said engine, extending into said bearings and revolvably suspending said engine therefrom and therebelow, and gearing connections between said engine and one of said tubular bearings for driving said shell from said engine.

45 3. A bomb construction comprising a spherical shell, spaced parallel partitions within said shell, dividing said shell into charge receiving chambers and an intermediate engine chamber, an internal combustion engine within said engine chamber, said engine including a fuel tank and an air mixer, tubular bearings extending diametrically through said shell and partitions and inlet and outlet or exhaust conduits fixed to said engine, extending into said bearings and revolvably suspending said engine therefrom and therebelow, and gearing connections between said engine and one of said tubular bearings for driving said shell from said engine.

50 4. A bomb construction comprising sections of a sphere each having a partition forming a charge receiving chamber within said section and each provided with a tubular bearing extending completely through its chamber and through the section wall and partition, said sections being

connected to form a sphere with their respective partitions in spaced relation, and the aforesaid tubular bearings alined, an internal combustion engine within the space between said partitions, inlet and exhaust conduits fixed to said engine, extending into said bearings and revolvably suspending said engine therefrom and therebelow, and gearing connections between said engine and one of said tubular bearings for driving said shell from said engine.

5. A bomb construction comprising two semi-spherical sections each provided with a partition forming a charge receiving chamber and each partition disposed inwardly of its section relatively to its edge, said partitions, in assembled 15

relation being parallel and spaced to provide an engine receiving chamber therebetween, a tubular bearing extending completely through the chamber of each section and through the section wall and, in assembled relation, alined one with the other, an internal combustion engine within said space between said partitions, inlet and exhaust conduits fixed to said engine, extending into said bearings and revolvably suspending said engine therefrom and therebelow, and gearing connections between said engine and one of said tubular bearings for driving said shell from said engine.

SAMUEL L. CONRAD.
